UNITED STATES PATENT OFFICE.

CHARLES W. BLODIE, OF CHICAGO, ILLINOIS, ASSIGNOR TO THE WILLIAM SCHOLLHORN COMPANY, OF NEW HAVEN, CONNECTICUT, A CORPORATION OF CONNECTICUT.

HAND-TOOL.

1,206,199.

Specification of Letters Patent. Patented Nov. 28, 1916.

Application filed January 12, 1915. Serial No. 1,794.

To all whom it may concern:

Be it known that I, CHARLES W. BLODIE, a citizen of the United States, residing in the city of Chicago, county of Cook, State 5 of Illinois, have invented certain new and useful Improvements in Hand-Tools, of which the following is a full, clear, and exact description.

This invention relates to hand tools, and 10 it has special reference to tools of the plier or lever handle type, such as shown, for example, in Patent No. 479,113 granted to W. A. Bernard on July 19th, 1892, or Reissue Patent No. 13,657, granted to W. A. Bernard on December 16th, 1913, although certain features of the invention are applicable 15 to tools of other types.

One of the primary objects of the invention is to provide improved means for adjusting the jaws of a cutter or like device 20 relative to each other, so that as the cutting edges are worn down and re-sharpened they can be maintained in proper relation to each other.

25 Another object of the invention is to provide a compound tool having a plurality of pairs of movable jaws and a single operating means therefor in combination with adjusting means whereby the tool may be so adjusted that both or all of said pairs 30 of jaws will close together completely at the same time, even though one or more of said pairs of jaws are considerably worn or ground down.

35 Another object of the invention is to provide improved means for adjusting the throw or movement of a pivotally mounted jaw actuated by lever handles or the like.

To these and other ends the invention consists 40 in the novel features and combinations of parts to be hereinafter described and claimed.

In the accompanying drawing, Figure 1 is a side elevation of a pair of pliers embodying my improvements, with the jaws open, Fig. 2 is a fragmentary elevation showing the jaws closed, Fig. 3 is a view 45 similar to Fig. 2, showing the adjustable jaw in another position, after it has been worn away and re-sharpened, Fig. 4 is a section on line 4—4 of Fig. 2, Fig. 5 is a fragmentary side elevation of the tool with the pivot member and its adjustable carrier removed, and Fig. 6 is a detail perspective 50 view of the carrier and pivot screw.

In the drawing I have shown my improvements applied to pliers of the kind illustrated in the Bernard Patent No. 479,113, and I shall proceed to describe the details of construction in that particular connection, but it will be understood that in many phases of the invention the general type of the tool may be considerably varied. 60

Referring to the drawing the tool comprises jaws 10, 11, adapted to be operated by pivoted levers or handles 12, 13. The jaws 10, 11, which may be called the main or primary jaws, are of the so-called parallel type. The handles 12, 13 are forked at their forward portions as usual, and these forked 70 portions are crossed and pivoted together by means of separate pivots 14, 15, at opposite sides of the tool. In other words, the side portion or tine of one fork is pivoted to the adjacent side portion or tine of the other handle by a separate pivot at one side 75 of the tool and substantially the same arrangement in this respect is adopted at the opposite side. The jaws 10, 11 have the usual form of plier jaws. The jaw 10 is pivoted by a pin or bolt 16 to the forward extremity of the fork of the handle 13, and the jaw 11 is similarly pivoted by means of a pin or bolt 17 to the forward extremity of the fork of the handle 12. The jaws 80 10, 11 are slotted at their rear portions, as shown by the dotted lines in Fig. 2, and the slots engage the pins 18, 19, mounted in the handles in the usual manner. This is a well known method of mounting the jaws for 85 parallel movement to which I make no claim. 90

The jaw 10 is provided at its outer part (i. e. at the side opposite its inner working surface) with an enlargement 20, which forms in effect an auxiliary or subsidiary 95 jaw. Coöoperating with this subsidiary jaw 20 is a pivoted subsidiary jaw 21. In the form shown the subsidiary jaws 20, 21 form a so-called side cutter for which purpose they are provided with beveled coöoperating 100 cutting jaws 22, 23 respectively. The jaw 21 is provided with a perforation engaging the pivot bolt 16, as in the Bernard Patent No. 479,113, whereby said jaw is pivoted to the forward extremity of the handle 13. The 105 jaw 21 is likewise pivoted on a pivot member or screw 15^a associated with the pivot device 15 for the lever handles, so that as the main jaws 10, 11 are closed together by the handle levers the subsidiary jaws 20, 21 will 110

approach each other at the same time. Similarly, when the jaws 10, 11 are separated by the actuation of the lever handles 12, 13, the subsidiary jaws 20, 21 will likewise be 5 separated.

- In accordance with the present invention one pair of jaws is adjustable relatively to the other pair, so that if desired the tool may be so adjusted that both pairs of jaws 10 will be completely closed together at the same moment, even in case one or both pairs of jaws have become considerably worn by use, or have been considerably ground away by sharpening or otherwise. In the form 15 shown the pivoted subsidiary jaw 21 is adjustable relatively to its coöperating jaw 20 and relatively to the main jaws 10, 11. To this end one of the pivotal points of support of the jaw 21 is adjustable relatively to the 20 lever handles and to the main jaws. In the example shown the pivot screw 15^a for pivoting the rear end of jaw 21 is mounted eccentrically in an adjustable carrier 24, which can be turned on an axis coincident 25 with the pivot of the levers 12, 13. The carrier 24 is preferably in the form of a disk or cam having an eccentrically located perforation or bearing 25 for the pivot screw 15^a. The body portion of the carrier 24 is 30 of cylindrical form and fits within a corresponding recess 27 in the overlapping arm or plate portions 12^a, 13^a of the levers 12, 13 at one side of the tool. The plate portion 12^a of lever 12 and the adjusting plate 35 portion 13^a of lever 13 are provided with registering perforations creating the recess or socket 27, in which the body of the carrier 24 is inserted for turning movement. The pivot screw 15^a has a smooth cylindrical 40 bearing portion 15^b, fitting the eccentric perforation or bearing 25 in the member 24 and at its inner extremity the threaded shank 15^c of the screw is screwed in the usual manner into a tapped opening 28 in the subsidiary jaw 21. At its outer part the member 24 is provided with a lateral flange 26 overlying the opening in the plate portion 12^a and provided with one or more notches 27^a. 45
- By the construction described it will be 50 apparent that the carrier or cam 24 may be turned on its axis within the socket 27 by engaging a screw-driver, spanner or like tool, with the notches 27^a. It will also be observed that inasmuch as the screw 15^a is 55 eccentrically located with respect to the carrier the screw will be displaced relative to the handles as the carrier is turned on its axis. By referring to Figs. 1 and 3, it will be noted that by turning the carrier or cam 24 on its axis the pivot screw 15^a may be 60 raised and lowered relatively to the tool so as to move the jaw 21 (pivoted to the screw) closer to or farther away from its coöperating jaw 20.
- 65 It is manifest that when a tool of this

character leaves the factory both pairs of jaws should close together perfectly. In other words, when the plier jaws 10, 11 are in light contact the cutting edges 22, 23 of the subsidiary jaws 20, 21 ought to be in 70 light contact. Supposing that the cutting edges 22, 23 are worn away by constant use and are re-sharpened along the dotted lines in Fig. 2, it will be evident that the proper adjustment of the two pairs of jaws relative 75 to each other is no longer maintained. I can provide this adjustment, however, by the construction herein described, in which it is merely necessary to turn the cam or carrier 24 in such a direction as to approach the pivot member 15^a toward the jaw 10 to a slight extent, thereby bringing the cutting edges of the subsidiary jaws again into contact when the main jaws are brought into contact as shown in Fig. 3. Thus the adjustable carrier for the pivot member 15^a 80 permits the subsidiary jaws to be brought fully together even after they have been considerably worn. On the other hand, if it is found that the subsidiary jaws meet each 85 other before the main jaws are closed the cam or carrier is turned in such a direction as to permit the subsidiary jaws to move away from each other to the required extent. In the form shown, the member 24 forms the 90 pivot proper for the lever handles at one side of the tool, although the screw 15^a or its equivalent is necessary to hold said member in place and to form the complete pivot device 15 hereinbefore mentioned. The 95 screw 15^a forms a pivot for the jaw 21, and obviously it is adjustable with respect to the pivot member 24 for the handles when the latter member is turned on its axis, as hereinbefore described.

100 It will be apparent that the construction is quite simple and that the tool can be readily assembled. Of course it is not always necessary to use the adjusting mechanism for closing all the various jaws at 110 the same time, because in some cases it might be desired to close one pair of jaws before the jaws of another pair came into full contact with each other.

I have only shown and described one embodiment of my invention, but it will be understood that the invention is susceptible of numerous other embodiments within the scope of the claims.

115 What I claim is:

- 120 1. In a hand tool, a pair of parallel jaws, a pair of lever handles for operating said jaws, a pivoted subsidiary jaw coöperating with one of said parallel jaws, means for operating said subsidiary jaw from said lever handles concurrently with the parallel jaws, and means for adjusting said subsidiary jaw relatively to said parallel jaws; substantially as described.

- 125 2. In a hand tool, the combination of a

- pair of parallel jaws, one of said jaws having a subsidiary jaw thereon, a pivoted subsidiary jaw, a pair of lever handles for closing all of said jaws, and means for adjusting 5 the pivoted subsidiary jaw relatively to the parallel jaws so that it will be completely closed when the parallel jaws are completely closed; substantially as described.
3. In a hand tool, the combination of a 10 pair of parallel jaws, a pair of crossed lever handles, means for pivoting said lever handles at the point where they intersect, means for pivoting the forward ends of the lever handles to said parallel jaws, means 15 guiding said jaws for parallel movement, and a subsidiary jaw pivoted coincidently with one of said parallel jaws, said subsidiary jaw being also pivoted adjacent the pivot of the lever handles but adjustable 20 relatively to said pivot; substantially as described.
4. In a hand tool, a pair of parallel jaws, a pivoted subsidiary jaw, a pair of lever handles for operating all of said jaws, and 25 means for adjusting the pivoted subsidiary jaw relatively to the parallel jaws; substantially as described.
5. In a hand tool, a pair of jaws, a pair 30 of operating lever handles for said jaws adapted to give the latter a parallel closing movement, a pivot for said lever handles, pivots connecting the respective lever handles with the respective jaws, a pivoted subsidiary jaw supported on one of said last 35 named pivots and on the pivot of the lever handles and means for mounting said subsidiary jaw adjustably relatively to one of said pivots; substantially as described.
6. In a hand tool, a pair of main jaws, a 40 pair of operating lever handles for said jaws, connections between said handles and said jaws for giving the latter a parallel movement, including pivots connecting the
- forward extremities of the respective handles with the respective jaws, a pivot connecting 45 the lever handles, a subsidiary jaw mounted on said last named pivot, and also on one of said first named pivots, and means for adjusting said subsidiary jaw relatively to the pivot interconnecting the handles; sub- 50 stantially as described.
7. In a hand tool, the combination of a pair of crossed lever handles, a pivot member for said handles by which they are pivoted together, a jaw pivoted to one of said 55 lever handles at one side of said pivot member and slideable relatively to the other handle at the other side of said pivot member, a swinging jaw to coöperate with the first jaw pivoted coincidently with said first 60 jaw, and means to pivot said swinging jaw to the pivot member of said lever handles, said last-named means adjustable to shift said swinging jaw relatively to said pivot member; substantially as described. 65
8. In a hand tool, the combination of a pair of parallel jaws, a pair of lever handles having forked portions crossing each other and pivoted to the respective parallel jaws, means guiding said jaws for parallel move- 70 ment, the forked portions of said levers having registered openings at one side of the tool, a pivot member for said lever handles, engaging said openings, and adapted to be turned therein, a swinging subsidiary jaw 75 pivoted coincidently with one of said parallel jaws, and a pivot member for said subsidiary jaw having an eccentric bearing in said first named pivot member; substantially as described. 80

In witness whereof, I have hereunto set my hand on the 8th day of January, 1915.

CHARLES W. BLODGETT.
